CLAIM

The ornamental design for a ventilated shirt, as shown and described.

DESCRIPTION

FIG. 1 is a front view of a ventilated shirt, showing a new design;

FIG. 2 is a back view of the ventilated shirt;

FIG. 3 is a side view of the ventilated shirt shown in FIG. 1;

FIG. 4 is a top view of the ventilated shirt of FIG. 1; and, FIG. 5 is a bottom view of the ventilated shirt of FIG. 1. The broken line showing of the shirt is for illustrative purposes only and forms no part of the claimed design.
